UNITED STATES PATENT OFFICE.

CHRISTIAN BRYNOLDT, OF PITTSBURGH, PENNSYLVANIA, ASSIGNOR TO BLAW-KNOX COMPANY, A CORPORATION OF NEW JERSEY.

FLOOR FORM.

Application filed April 13, 1920. Serial No. 373,529.

This invention relates to floor forms and is particularly useful in connection with flat slab construction.

One of the primary objects of my invention is the provision of an improved floor form which is of simple construction and which may be readily collapsed and telescoped through the work or through other forms in place.

Another object of my invention is the provision of an improved form for column supported floors.

My invention also contemplates the provision of improved means for supporting the form whereby the same may be readily and quickly taken down without interference with adjacent units.

The general object of my invention is to effect an economy in the permanent plant investment and in the time and labor ordinarily required in this class of work.

The foregoing, together with such other objects as may hereinafter appear, I obtain by means of a construction which I have illustrated in preferred form in the accompanying drawings, wherein:

Fig. 1 is a vertical section taken through form apparatus embodying my invention on the line 1—1 of Fig. 2; Fig. 2 is a top plan of the apparatus thereof broken away to more clearly illustrate the structure; Fig. 3 is an enlarged side elevation of that portion of Fig. 2 between the arrows marked 3—3; Fig. 4 is a section taken on the line 4—4 of Figs. 1 and 2, on an enlarged scale; Fig. 5 is a fragmentary section illustrating a portion of the floor form in collapsed position ready to be telescoped through the work and set up at a new point, and taken on the line 5—5 of Fig. 2; Fig. 6 is an end elevation of the centre panel and the side or wing panels in collapsed position; Fig. 7 is a side elevation of an end panel and one of its sides or wings in collapsed position, together with the traveler therefor; Fig. 8 is a view similar to Fig. 7 showing an end panel and its plinth and capital or column head mold section in collapsed position; Fig. 9 is an enlarged side elevation of the traveler for the centre panel, illustrating the manner in which the panel is supported thereon; Fig. 10 is a fragmentary plan view of a detail of the traveler shown in Fig. 9; Fig. 11 is an enlarged section taken on line 11—11 of Fig. 2; Fig. 12 is an enlarged section taken

on line 12—12 of Fig. 2; Fig. 13 is an enlarged section taken on line 13—13 of Fig. 2; Fig. 14 is a fragmentary side elevation, drawn on an enlarged scale, of that portion of the apparatus between the arrows marked 14—14 of Fig. 2; Fig. 15 is an enlarged section taken on the line 15—15 of Fig. 2; Fig. 16 is a view illustrating a detail of the means carried by the traveler for collapsing portions of the form; Fig. 17 is a side elevation of a portion of the column form, drawn on an enlarged scale; and Fig. 18 is an enlarged detail of the joints utilized for hinging the swinging portions of the form to the panels.

Referring now to Fig. 1 the shores, which are preferably set up in rows forming bays, and on which the forms are to be supported, are indicated at 7. 8 are the shank molds for the columns A. Depending upon the length of the form, considered as a unit, the form comprises one or more centre panels, B; end panels, C; wing or side panels, D, carried at either end of the centre panel; side or wing panels E, carried by the end panel, C; and the combined plinth and capital or column head sections F and G, respectively carried by the centre panels and the end panels. Each end panel, therefore, has two wing panels, and a combined plinth and capital mold section, while the centre panels have two wings and a combined plinth and capital section at each end, so that when the parts are assembled and positioned as shown in Figs. 1 and 2 a practically complete form for a section of the floor results. The preferred construction of the various parts will now be described.

The centre panel B comprises a frame composed of a pair of longitudinal channels 9 and a plurality of transverse channels 10 secured to the channels 9 in any preferred manner. Carried on the channels 10 are plurality of nailing strips 11 to which the lagging 12 is nailed, see Figs. 1, 2, 3 and 5, for example.

The shores 7 on either side of the columns are provided near the top with brackets 13, detachably secured to the shores one on each side. Pairs of channels 14 and 15 are placed on the brackets 13 in the manner indicated in Figs. 3 and 4 and the channels 9 of the frame of the central panel rest on the ends of these channels.

The wings D consist of a framework com-

prising a channel 16, a channel 17, the transverse channels 18, secured to the lower faces of the channels 16 and 17 and the angles 19, secured to the bottoms of the channels 18 and spaced apart to receive the eye of a ratchet jack 20 (see Figs. 2, 3 and 13). This frame carries the nailing strips 21 to which the lagging 22 is nailed. Each of the channels 16 and 17 is secured by a pivotal connection 23 to a channel 9 of the central panel frame, the details of this connection being illustrated in Figs. 13 and 18. The channels 17 of the wings D project well beyond the free end of the wing frame.

15 The wings E are constructed in substantially the same manner as the wings D, practically the only difference being that the corresponding channel 17 is offset with respect to the channel 17 on the adjacent wing D so that the two channels may lap past each other as indicated in Figs. 2, 3 and 14. The frames of the wings E are pivoted to channel 9^a of the frame of the end panel C. When the wings D and E are in the position shown in Fig. 3 the inner portion of their frames, that is to say, those portions nearest to the respective column, are supported against depression under load by the brackets 24 which are carried by the channel 14 20 in position to support the free ends of the channel 16 of the wing frames (see Figs. 4 and 15). The outer ends of the wing frames are supported against depression under load by detachably bolting together the overlapping ends of the channels 17, as diagrammatically indicated at 25 in Figs. 3 and 14.

25 The end panels C are composed of a frame-work of structural members such as the channel 9^a and the channels 26 and 29, the latter being secured to the channels 26; the nailing strips 27 carried on the channels 26; and the lagging 28. The end frames are supported in the position shown in Figs. 1 and 3 on the ends of the channels 14 and 15 and by the channel 30 which is carried on the detachable brackets 31 on the end row of shores 7.

30 The frames for the combined plinth and capital sections G and F consist of the channels 32, the pairs of spaced angles 33, and the channels 40. The stringer 34 is carried on the angles 33 and the nailing strips 35 are carried on one of the channels 32 and the stringer 34, the lagging 36 being secured to the nailing strips, see Figs. 2 and 11.

35 The capital form consists of two half-molds 37, each of which is carried from the frame of the respective plinth section in the following manner: Secured to the top of each half capital mold is a semicircular channel 38 which rests upon and is secured to one of the channels 32. The ends of the channel 38 are supported by means of the brackets 39 secured to the channel members 40 constituting a part of the frame work

of the members G and F. These brackets 39 also serve as a support for nailing strips for the lagging 36.

40 The frames of the members G and F are prevented from sagging under load by virtue of the fact that the channels 40 are provided with clips 41 which rest upon the channels 35. See Figs. 2, 4 and 12.

45 It will be understood that the frames for the members D and E, and G and F are hinged or pivotally connected to the frame of the adjacent panel member by the pivotal connections 23. It will also be understood that a pair of jacks 20 is provided for each plinth member, the eyes of which are secured to the angles 33.

50 The side walls of the plinths are formed by the members 42 which are secured to the channels 16 of the wings E and D, and by the filler members 43 which are secured in position by means of the brackets 44 connected to the channels 9 or 9^a, as the case may be. The gap between the wings E and D and the sections G and F is closed by stringers 45 which rest upon the tops of the shores 7 (see Figs. 2, 4 and 15). At the ends of the units I also provide stringers 46 (see Fig. 3 at the left) on which are supported the strips 47. Such strips acting as a filler member fill the gap between the end of adjacent units or between an end of the unit and some other portion of the structure.

55 With the parts positioned as described it will be clear that they will be securely supported. The means whereby the forms may be collapsed and lowered for telescoping through the work or through other forms in place, will now be described.

60 For a center panel, a traveler H is provided which rides on rails 50 extending longitudinally of the bay, and for an end panel a traveler I is provided. On reference to Figs. 1, 5 and 9, it will be seen that the traveler H comprises a suitable frame-work built up of structural members having four 65 guide posts 51 which slidably receive the posts 52 which carry a platform composed of structural members. When the platform is elevated by raising the posts 52 by mechanism which will hereinafter be described, the platform is brought up against the channels 10. The traveler I is of the same general construction, but is provided with a pair only of guide posts 51 and elevating posts 52 and when the latter are elevated the platform is brought in to engagement with the channels 26 of the end panel frame.

65 Assuming now that the travelers are in the position indicated in Fig. 1, to collapse the form, the bolts 25 are removed freeing the members 17; the brackets 24 are removed, which frees the wing members E and D for collapse by their respective jacks; the brackets 44 are removed; and the chan-

nels 14 and 15 are taken down by first removing the brackets 13. All of the parts with the exception of 45 and 46 are now supported from the travelers. The jacks 20 are now operated to swing the sections or wings E and D and the sections F and G downwardly, it being understood that the shank molds of the columns are first removed. Because of the amplitude of movement, the jacks 20 are insufficient to swing the sections all the way down and to meet this condition I have provided the following mechanism: Each jack 20 has an eye secured to an angle 55 running longitudinally of the traveler platform, there being a pair of such angles 55 one for the set of jacks on one side of the traveler and the other for the set of jacks on the other side of the traveler. At each end, the angles 55 are provided with an angle clip 57 to which is secured a vertical plate 56. The angles 55 are supported on the cross channels 58 of the traveler platform and the angle clips 57 and the plates 56 are so disposed as to lie on the outside of the channels 58. At the bottom each plate 56 is provided with an angle clip 59 adapted to engage the bottom of the channels 58. By this construction the angles 55 are slidably yoked to the channels 58. At the end of the angles 55, I provide jacks 53 secured to the angles 55 by means of the angle clips 59, the other end of the jacks being secured to angle clips 60 which are in turn secured to the channels 58. The jacks 53, therefore, operate to shift the angles 55 toward and away from the centre of the traveler platform. When the parts are in the position shown in Figs. 1 and 3 the jacks 53 are shortened, while the jacks 20 are fully lengthened. In collapsing, the jacks 20 are first fully shortened, which partly brings the swinging members downward, after which the jacks 53 are lengthened which shifts the angle 55 to the centre stop 61, as shown, for example, in Fig. 6. This brings the swinging parts in full down position.

The jack arrangement for the end panel is fundamentally the same, the only differences being those that are incident to the fact that the traveler I has but one set of jacks for its wings and plinth sections.

In Figs. 7 and 8 the end panel wing section and the plinth section are shown in collapsed position.

When the swinging sections have been swung downwardly or collapsed, the platform of the travelers are lowered clearing the form and permitting it to be telescoped and set up at a new point. The means for raising and lowering the traveler platforms will now be described, attention being directed to Figs. 9 and 10.

Ratchet jacks 65 having one end connected to the traveler frame and the other end connected by suitable links 66 to beams 67,

are provided. The beams 67 are pivoted to the traveler frame much closer toward one end than the other so as to greatly amplify the movement imparted by the ratchet jacks. The outer ends of the beams 67 are connected to the elevating posts 52 by suitable means such as the turnbuckle links 68.

Among the advantages incident to the construction are the fact that the initial plant equipment and, therefore, the initial investment are greatly reduced because the form apparatus can be taken down after a relatively short time and set up for reuse, etc., etc. In this connection, attention is directed to the fact that the members 45 and 46 which are carried on the shores and which remain in position, are sufficient to support the concrete until it is thoroughly set. The apparatus is relatively easy to manipulate and effects a great saving in time, labor and materials over the ordinary methods followed in this art. It will also be seen that the form, considered as a unit, may be taken down without interference with an adjacent unit and that if desired certain portions of a unit may be taken down without disturbing the remaining portions.

It will also be seen that in setting up the device the travelers may be used to shift the parts and support them into the proper position until channels 14 and 15 and the various brackets hereinbefore referred to are set up and secured, after which the traveler apparatus may, if desired, be detached and used elsewhere either to take down or set up for other units. It will be apparent that the apparatus has great utility where operations are to be carried out on a large scale.

What I claim is:—

1. A mold form apparatus for concrete floors and the like comprising in combination false work, a collapsible mold form section, means detachably supporting the section from the false work, mold means carried by the false work adapted to be left in position until the concrete sets and a traveler for taking down the collapsible section and transporting it, said traveler being provided with means for collapsing the mold section.

2. A mold form apparatus for concrete floors and the like comprising in combination false work, a collapsible mold form section, means detachably supporting the section from the false work, mold means carried by the false work adapted to be left in position until the concrete sets, and means for taking down the collapsible section, said last means including means for collapsing the said mold section.

3. A mold form apparatus for column supported floors and the like comprising the combination of a panel mold section, a column mold section connected therewith for collapsing movement, means for releasably supporting the column section in operative

- position, and means for collapsing the column mold section whereby it and the panel mold may be taken down as a unit.
4. A mold form apparatus for column supported floors and the like comprising the combination of a panel mold section, a column mold section connected therewith for collapsing movement, means for releasably supporting the section in operative position, and a take down mechanism for taking down the sections as a unit.
5. A mold form apparatus for column supported floors and the like comprising the combination of a panel mold section, a column mold section connected therewith for collapsing movement, and means for releasably supporting the sections in operative position to permit of collapse and taking down as a unit.
- 10 6. A mold form apparatus for column supported floors and the like comprising the combination of a removable column mold, a capital mold section and a panel mold section with which the capital mold section is connected for collapse whereby the two may be taken down as a unit.
- 15 7. A mold form apparatus for column supported floors and the like comprising the combination of a removable column mold, a combined capital and plinth mold section and a panel mold section with which the
- capital mold section is connected for collapse whereby the said sections may be taken down as a unit.
8. A mold form apparatus for column supported floors and the like comprising the combination of a removable column mold, a plinth mold section, and a panel mold section with which the capital mold section is connected for collapse whereby the two may be taken down as a unit.
- 35 9. Mold form apparatus of the character described comprising floor mold sections articulated together, means including false-work uprights for normally supporting said sections substantially horizontal releasable to permit them to be folded together between the falsework uprights, and means for thus collapsing the sections and lowering them between said uprights.
- 40 10. A mold form apparatus for floors and the like comprising in combination a pair of substantially horizontally disposed spaced mold sections, a swinging mold section secured to each of the spaced mold sections and adapted to substantially close the space therebetween, and means for releasably supporting the free ends of the swinging sections.
- 45 50 In testimony whereof, I have hereunto signed my name.

CHRISTIAN BRYNOLDT.
